UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS FOR PRODUCING LOW BOILING POINT HYDROCARBONS

Original application filed November 4, 1918, Serial No. 260,955. Divided and this application filed September 6, 1921, Serial No. 498,886. Renewed July 16, 1928.

This application is a divisional of an original application filed by me under date of November 4, 1918, Serial No. 260,955.

This invention relates to a process for treating hydrocarbon oils to produce therefrom products having lower boiling points.

The objects of the invention are to provide a process for separating oils of different boiling points; to provide a process wherein the

10 oil under treatment is circulated through a coil and then to and from a vapor chamber, which latter chamber is only partly filled with the oil, the oil being heated as it passes through the former coil and as it passes

15 through the latter chamber it is relieved of more or less of its vapor content, which vapors pass to and through a condenser while more or less of an insoluble material, such as carbon formed in the oil, settles and is drawn

20 off while the remaining unvaporized oil passes from the vapor chamber back to and through the heating tubes, the whole being maintained under pressure; to provide a process in which the heating of the oil under

25 treatment is accomplished in the heating coils and said oil maintained in rapid circulation in these coils and then discharged into one end of the vapor chamber, said chamber being only partially filled with the oil and said

30 oil withdrawn from said chamber at the other end forced back through the heating coil, while more or less of the oil and carbon and other solids are drawn off as residuum, said vapor chamber being of such size in the

35 cross section as to greatly reduce the speed of the flow of the oil from one end to the other and said chamber being of such dimensions as to permit more or less of its solid content to settle out and means being provided for

40 the drawing off of more or less of the solids that are thus settled out of the oil along with part of the oil and means provided for supplying fresh oil to the apparatus; to provide a process for continuous operation; to pro-

45 vide a process in which those products that are only partly reduced or converted to the desired low boiling point, are returned and further circulated through the heating tubes; to provide a process in which the vapors not

50 having the desired low boiling points are con-

densed and automatically returned for further treatment; to provide a process whereby the free carbon produced can be settled out and removed without interrupting the operation; to provide a process for alternately 55 heating the hydrocarbons, relieving same of its generated vapors and further heating the remaining liquid hydrocarbon.

In the drawings:

Fig. 1 is a side elevation of an apparatus 60 substantially along line 1—1 of Figure 4, partly in section, and with parts broken away, in which my improved process may be carried out.

Fig. 2 is a plan view of the apparatus. 65

Fig. 3 is a plan view showing that section of the furnace containing the heating tubes.

Fig. 4 is one end view of the apparatus, partly in section, with parts broken away.

Referring in detail to the drawings, A 70 is the furnace proper with fire tunnel A—1, perforated arch wall A—2, flue tunnel A—3, stack A—4. Positioned in the furnace A are the heating coils B and B—1 connected with pumps C and C—1 by means of pipes D and D—1. D—2 is the pipe connecting vapor chamber E to pump C and D—3 is line connecting pump C—1 with the separating chamber F and said chamber F is connected to vapor chamber E by means of line F—1. 75

The coils B—1 are connected by line D—4 to vapor chamber E. G is the vapor line connecting with manifold G—1 which by means of pipes G—2, G—3, G—4 and G—5 is connected to manifold G—6, which latter manifold is connected by means of pipe G—7 to water cooled condenser coil G—8, positioned in tank G—9, and by means of pipe G—10 is connected with receiving tank H, which has positioned on it pressure regulating valve 80

H—1, glass liquid gauge H—2, drawoff line H—3 with valve positioned on it marked H—4. K—1, K—2, K—3, K—4, K—5 and K—6 are pyrometers of standard make. L—1, L—2 and L—3 are pressure gauges and 85

may be either indicating or recording. M is a glass liquid gauge on the end of the retort E. P is the supply tank for the raw material to be treated and is connected by means of line P—1 to pressure pump P—2, which 90

95

L—1, L—2 and L—3 are pressure gauges and may be either indicating or recording. M is a glass liquid gauge on the end of the retort E. P is the supply tank for the raw material to be treated and is connected by means of line P—1 to pressure pump P—2, which 100

discharges into line D through line P—3. R and R—1 are drawoff lines from the retort E. 1, 2, 3, 4, 5 and 6 are valves. X and X—1 are cleaning plates.

- 5 Describing now the operation of the process, the material to be treated may be drawn from any suitable source of supply, as for instance as shown in the drawing, from tank P in which the raw material to be treated **may** 10 be stored. This tank P is connected by means of pipe P—1, pressure pump P—2, which discharges through line P—3 into line D into that section of the heating coils marked B and from there discharges into separating 15 chamber F. The vapors generated pass off from chamber F through line F—1 into vapor chamber E while the unvaporized portion of the oil passes from chamber F through line D—3 into pump C—1, through line D—1 20 into heating coils marked B—1 and from there pass through line D—4 into vapor chamber E. The vapors generated and accumulated in the vapor chamber E pass up through goose-neck G into manifold G—1 through pipes G—2, G—3, G—4 and G—5 into manifold G—6 and such vapors that are condensed therein are automatically drained back to retort E and subjected to further treatment, while the 25 30 remaining vapors pass from manifold G—6 down through line G—7 through water cooled coil G—8, through line G—10 into receiver H and from which it can be drawn off continuously or intermittently through line H—3 35 through valve H—4. The excess uncondensable gases are automatically relieved through pressure regulating valve H—1 or it may be relieved through an ordinary valve (not shown). The oil in the vapor chamber E, passes down through line D—2 into the suction end of pump C and is forced by this pump through the line D, through coils marked B, positioned in the furnace A and discharged into separating chamber F as 40 45 already described.

Pressure gauges and pyrometers are positioned in different places in the apparatus so that the proper temperatures and pressures may be maintained. Such pressures and 50 temperatures will vary according to the oil being treated, the extent of the cracking taking place, etc. The oil in the vapor chamber E must be always maintained above the outlet to D—2 in order to insure a full supply being furnished the pump C. The supply of oil to separating chamber F should be sufficient to keep the pump C—1 supplied with oil.

Maintaining a high velocity on the oil 60 while passing through the heating tubes will tend to keep the carbon and other solid matters in suspension and to a great extent, prevent same from adhering to the walls of the tubes and when this oil is discharged into one 65 end of the vapor chamber E, the vapor cham-

ber E being of much larger capacity, the velocity of the oil as it flows from one end of the vapor chamber E to the other end thereof, is greatly reduced and any excess carbon or other solid matters that are held in the 70 solution or suspension by means of a higher agitation or velocity, will be precipitated out in the vapor chamber E and there held while the oil is drawn off and again passed through the heating coils in the furnace A and subjected to further treatment. In order to have a large capacity vapor chamber and prevent substantial vaporization taking place in the heating tubes, I have provided a separating 75 chamber F to be interposed between the heating coils and into which the oil is discharged and relieved of its vapors and then by means of another pump sent back through the furnace in other coils and then discharged into one end of the vapor chamber and as many 80 of these chambers and pumps can be used as is found necessary to handle the desired capacity of the plant. The residuum and more or less of the carbon and other solid 85 matters that settle in the vapor chamber are 90 drawn off through lines R and R—1, either continuously or intermittently as likewise the raw material can be fed into the apparatus either continuously or intermittently.

It will be noted that the vapor chamber E 95 is positioned outside of the furnace A and is heavily lagged as likewise should be all pipes outside of the furnace in order to prevent heavy loss of heat by radiation.

The entire system is subjected to a pressure 100 either vapor or gas or otherwise, which pressure will range from 5 pounds to 500 pounds per square inch, the pressure used varying according to the conditions to be met, such as the particular oil under treatment and the 105 products desired. The temperature to which the oil will be heated will presumably vary from 400 to 1200 degrees F., though these limits are not absolute in either case.

I claim as my invention: 110
A process of converting heavy into lighter hydrocarbons, consisting in pumping oil first through a heating coil and to a separating chamber, then taking off the vapors from said chamber and passing them to a vapor chamber, passing the unvaporized oil through a second heating coil to the said vapor chamber, taking off vapors from the vapor chamber and condensing them and returning the unvaporized oil from the said vapor chamber to the 115 first coil, the oil being maintained under pressure of the generated vapors during treatment.

CARBON P. DUBBS.
